CLAIM

We claim the ornamental design for a [articulating mount unit] **mounting plate**, as shown and described.

DESCRIPTION

[FIG. 1 is a perspective view of the articulating mount unit showing our new design;]

[FIG. 2 is a left side view thereof;]

[FIG. 3 is a right side view thereof;]

[FIG. 4 is a front view thereof;]

[FIG. 5 is a rear view thereof;]

[FIG. 6 is a top plan view thereof;]

[FIG. 7 is a bottom view thereof;]

[FIG. 8 is a perspective view of another embodiment of the articulating mount unit showing our new design;]

[FIG. 9 is a left side view of the articulating mount unit in FIG. 8;]

[FIG. 10 is a right side view of the articulating mount unit in FIG. 8;]

[FIG. 11 is a front view of the articulating mount unit in FIG. 8;]

[FIG. 12 is rear view of the articulating mount unit in FIG. 8;]

[FIG. 13 is a top plan view of the articulating mount unit in FIG. 8; and,]

[FIG. 14 is a bottom view of the articulating mount unit in FIG. 8.]

[The broken lines in the drawings are for illustrative purposes only and form no part of the claimed design.]

FIG. 15 is a perspective view of a mounting plate showing our new design;

FIG. 16 is a front view thereof;

FIG. 17 is a right side view thereof;

FIG. 18 is a left side view thereof;

FIG. 19 is a top plan view thereof; and,

FIG. 20 is a bottom view thereof.

1 Claim, 3 Drawing Sheets

Matter enclosed in heavy brackets [ ] appears in the original patent but forms no part of this reissue; matter printed in italics indicates the additions made by reissue.
